(57) **CLAIM**

The ornamental design for a light emitting diode lamp, as shown and described.

DESCRIPTION

FIG. 1 is a perspective view of a light emitting diode lamp socket showing our new design, the light emitting diode lamp being attached with a metallic cap which is shown in broken lines for illustrative purposes only;

FIG. 2 is a top view thereof;

FIG. 3 is a front view thereof;

FIG. 4 is a bottom view thereof;

FIG. 5 is a right side view thereof;

FIG. 6 is a left side view thereof;

FIG. 7 is a back view thereof;

FIG. 8 is an enlarged perspective view showing a part of the light emitting diode lamp indicated by the arrow A in FIG. 1, with the light-transmissive cover tube being omitted; and, FIG. 9 is an illustrative front view showing the light emitting diode lamp attached with a different type of metallic cap which is shown in broken lines for illustrative purposes only.
